UNITED STATES PATENT OFFICE

ALFRED F. POWELL, OF WALNUT PARK, CALIFORNIA

WELL DRILLING BIT

Application filed April 7, 1930. Serial No. 442,154.

This invention relates to a well drilling bit and refers particularly to the type of well drilling bit employed in drilling through hard rocks by the hydraulic rotary method. 5 This invention is a continuation in part of my copending application Serial No. 283,219, filed June 6, 1928.

An object of the invention is to provide a drilling bit of the class intended for drilling 10 through hard or semi-hard rock by means of rolling cutters in which there is provided a means for imposing the load from the drill pipe directly upon the rolling cutters, whereby the pins and bushings employed for 15 reliably mounting the rolling cutters are for theoretical purposes, entirely relieved from this pressure.

Another object of the present invention is to provide means for directly driving the 20 rolling cutters of the drill bit from the rotation of the drill pipe so that the drilling torque is transferred directly from the drill pipe to the cutters, rather than being transmitted from the drill pipe to the rolling 25 cutters through the pins and bushings or other means.

A further object of the present invention is to provide a drill bit with a rotatably mounted head which is normally supported 30 upon the cutters.

A further object of the present invention resides in the provision of means for locking the driving gear means against torque, while permitting rotation with the drive 35 shank.

A further object of the present invention is to provide a driving gear in the form of a disc having faces for locking the disc against torque, while permitting axial motion of the 40 driving gear.

A further object of the present invention is to provide a drill bit in which with a given rotation of the drill pipe, the rotation of the 45 rolling cutters at the bottom of the well and the planetary movement of the cutters, is materially reduced when compared with other bits.

A further object of the present invention is to provide a drilling bit of the above type 50 in which the parts subject to rapid wear are

not integral with the main body and are therefore capable of being replaced at low cost.

It is well known, that the power that can be transmitted through a drill pipe with a 55 given fiber stress or torque is directly proportional with the rate of rotation of the pipe. Therefore, the higher the speed of rotation the greater will be the power that can be transmitted through the drill pipe to 60 the rolling cutters and as a result the greater the amount of work performed by the rolling cutters in penetrating and disintegrating the formation in boring the well.

Experience teaches that in practice due to 65 the nature of the work to be done by the rolling cutters, there is an optimum speed of the cutters to give the greatest progress in drilling with the most suitable load on the cutters. This optimum speed is found in practice to be much lower than the desired rate 70 of rotation of the drill pipe to transmit with reasonable strain the necessary power to the rolling cutters.

As an example, in drilling certain formations it is found that a planetary rate of rotation of the rolling cutters of approximately 20 R. P. M. is the optimum rate to produce the maximum progress of drilling the formation; whereas, to transmit the proper 75 power through the drill pipe, a speed of approximately 40 R. P. M. is desirable. The bit of the present invention is designed to permit the drill pipe to rotate at the desired speed to transmit the proper power for drilling operations with a low fiber stress, and included means by which this speed of rotation is reduced so that the rolling cutters have a planetary rotation sufficiently low to 80 give the greatest progress in drilling with 85 the most suitable load on the rolling cutters.

With the well drilling bit of the present invention it is found in operation that the drilling pipe is subjected to less torsional stress than with the bits heretofore employed, 90 thereby decreasing the hazard of a "twist-off" of the drill pipe in the bore hole. At the same time more power is supplied to the rolling cutters and a greater speed of drilling 95 attained.

In drilling wells by the drilling bits which have heretofore been in common use the abrasive action between the well formation and the cutters or teeth of the cutters has generally resulted in the cutters or teeth of the cutters becoming dull with use. With the well drilling bit of the present invention it is found in operation that the cutters or teeth of the cutters are subject to wear in such a manner as to maintain the teeth as sharp or sharper than they are on the new cutters, with the result that the bit continues to drill rapidly for a long period of operation.

Various further objects and advantages of the present invention will be apparent from the description of the preferred forms or examples of a drilling bit embodying the invention. For this purpose reference is made to the accompanying drawings in which there is illustrated the preferred form or forms of well drilling bit embodying this invention.

In the drawings:

Figure 1 is an elevation mainly in vertical section of the drilling bit.

Figure 2 is an elevation of the bit illustrated in Figure 1 with the cutters removed.

Figure 3 is a perspective of the removable drive gear employed in the well drilling bit of Figures 1 and 2.

Figure 4 is a fragmentary view illustrating the manner of wear of a cutter tooth or projection of the present invention.

Figure 5 is a similar view showing the manner of wear generally experienced with the cutter teeth or projections heretofore generally used.

Figure 6 is a diagrammatic illustration of a modified form of cutter and drive gear.

Referring to Figures 1 and 2 of the drawings, the drilling bit is illustrated as comprising a tubular central supporting and power transmitting or driving reamer shank 30 which is provided with a tapered pin 31 at its upper end and which serves as a means by which the drilling bit may be attached to a string of drill pipe and rotated at the bottom of a well hole. The upper part of said member 30 carries a plurality of reaming rollers 32 for straightening and reaming the hole drilled by the main cutters of the bit. These reaming rollers 32 are shown as mounted within recesses 33 in the member 30 on the reamer pins 34.

Above the reamer pins 34 there are provided longitudinal recesses 35 by which the pins may be inserted, and 36 indicates dowel pins for locking the reamer pins 34 in place. Openings 37 are indicated at the lower end of the pins 34 through which a tool may be inserted for knocking out the pins 34 when it is desired to replace the reaming cutter 32.

The lower part of the central supporting and power transmitting member 30 is reduced as indicated at 38, forming a downwardly turned annular shoulder 39. At the bottom

of the member 30 there is provided a socket, the lower portion of which is bevelled, as indicated at 40 and the upper portion of which is bevelled and rectangular as indicated at 41. The bore 42 of the member 30 provides an axial passage through which the flushing fluid may be supplied to the cutters of the bit.

43 indicates a tubular head which is revolvably mounted on the lower end of the central reamer shank 30 and at its upper end is provided with a socket 44 which receives an anti-friction bearing 45, the upper end of which, under certain circumstances, engages the shoulder 39 on the member 30. Above the shoulder 39 the member 30 is provided with an annular groove 45a which receives a packing to prevent drilling fluid from gaining access to the bearings 44. Said packing preferably comprises a rubber ring 46 which in operation is urged outwardly against the head 43 by pressure of drilling fluid entering the back of said ring through ducts 47.

Near the lower end of the member 30 there is provided an annular groove 48 which receives the ends of the head retaining pins 49 which are inserted in openings in the head 43 and extend into the bore of said head sufficiently to engage the groove 48 and prevent the head parting from the power transmitting member in the operations of inserting and removing the bit from the well hole. These pins are held in place by check nuts 51 threaded in said openings in the head 43.

The lower end of the head is provided with two diametrically opposed cutter shafts 52 which extend downwardly and inwardly into the space below the head and reamer shank 30. These shafts 52 are held in place by lock screws 53 passing through the upper ends of the shafts 52 and screwed into threaded openings in the head 43. On shafts 52 are mounted bushings 54 which are provided with recesses 55 at their inner ends which fit over bosses 56 on the end of the head for centering the bushings. The outer ends of the shafts 52 are provided with bores 57 which serve as lubricant holding chambers.

Upon the bushings 54 are mounted frusto-conical rolling cutters 58. These rolling cutters 58 comprise, in integral form, two frusto-conical cones united at their bases, one of the frusto-conical cones being provided with cutting teeth 59 while the other of said cones is formed with gear teeth 60.

The cutting teeth 59 of the cones and the shape of the cones are so designed that when the cones are given a planetary rotation by revolution of the reamer shank 30 around the axis of the well bore, the cutting teeth 59 will roll against the formation at the bottom of the bore hole, cutting ridges thereon, whereby the rolling cutters 58 become in operation meshed to the bottom of the bore hole. The cutters 58 are additionally provided with annular grooves 61 which serve to receive rings

of metal 62 serving to lock the cutters from movement axially with respect to bushings 54. Each of the cutters 58 is provided with radial openings 63 through which a tool may be inserted to engage a hole 64 in the bushing 54, whereby the bushing and cutters may be as a unit, be assembled upon the shafts 52.

At the lower end of the power transmitting member 30 there is a driving gear 65, illustrated in Fig. 3, the lower portion of which is a disc having a bevelled periphery 66 fitting the bevel 40 on the lower end of the member 30 and is also provided with a bevelled rectangular boss 67 fitting the bevelled rectangular socket 41 in the member 30. An axial orifice 68 with an enlarged entrance is provided in the driving gear 63 to permit the passage of drilling fluid from the bore 42 therethrough. Gear teeth 69 are provided on the lower face of the driving gear and are adapted to mesh with the gear teeth 60 on the rear frusto cones of the cutters 58. 70 indicates a packing ring engaging the lower end of the drive member 30 and held in the annular recess of the head 43.

The drive gear 65, driving member 30 and head 43 are so arranged and related that the engagement between the teeth of the driving gear and cutters 58 takes place at a point 30 which is approximately in the middle of the cutting teeth 59 at the bottom of the cutter. This permits the vertical load which, in operation is imposed upon the drill bit from the weight of the drill pipe connected therewith, to be transmitted directly from the drive member 30 to the cutters 58 centrally over the cutting zone without this weight having to be transmitted through pins and bushings connecting the cutter with the head 43. In 40 operation, therefore, this imposition of the load from the drive member 30 to the cutters 58 will substantially prevent any wear on the bushings or bore of the cones. Furthermore the outward thrust of the gear 45 operates to spread the cutters 58 in such manner as to compensate for any wear on the bushings and maintain the cutters in position where they cut the same size or larger bore hole, the weight of head 43 being normally supported upon the cutters 58.

In operation, as the bit is originally made, no pressure is received on the ball bearings 45. When the teeth 69 on the driving gear 65 wear away so that they are no longer able to transmit rotation properly to the cutters 58, weight becomes imposed upon the ball bearings 45. In such a case the driving member and drill bit are found to rotate smoothly in the bore hole without receiving 55 or absorbing any substantial power and the driller immediately notices that the bit has become worn and should be removed from the bore hole. This warning occurs without any danger of damaging the bit. The wear 60 members such as the drive gear 65, are made

readily replaceable, being held in place only by their contact with the rolling cutters 58.

The operation of the form of invention herein described is generally similar to that of my earlier application supra. In practice, 70 the rotation of the drive member 30 is imparted directly to the rolling cutters 58. These rolling cutters 58 cut into the formation at the bottom of the well and mesh themselves thereto. The rotation of the cutters 58 then effects a definite rotation of the head 43. The motion of the head 43 is approximately one-half of that of the drive member 30, although any desired ratio may be attained by proper sizing of the gear. 80

With the bit of the present invention, therefore, planetary rotation of the cutter as heretofore employed on other bits becomes positive, and approximately twice the power may be transmitted to the cutters through 85 the drill pipe without imposing upon the drill pipe more than normal strain.

Moreover, since the vertical load is imposed directly from the drive member 30 to the cutters 58, a greater load may be imposed 90 on the cutters if desired than is permissible with the ordinary type of rock drilling bits.

Another advantage of the present invention resides in the fact that the two cutters are connected to gearing means which insures 95 each cutter finding a proper fresh point in the formation to penetrate. If the cutters are made with an equal number of teeth and mounted loosely upon the bit, each cutter will merely follow around in the same tooth imprints produced by the previous cutter and little, if any, cutting action will be effected. By proper proportioning of the teeth on the gears with the bit of the present invention 100 the teeth on each cutter will strike the formation between the imprints of the teeth of the other cutter. 105

In Figure 4 the rear side 59c of the worn projection is slightly concave while both sides are worn down from the original shape of the projection, as indicated by the dotted lines 59d. The worn tooth, however, it will be noted, is fully as sharp as the original tooth. In Figure 5 there is illustrated in full lines 59e the shape of a worn tooth of a frusto-conical cutter operating on the type of bit previously employed as compared with the original shape of such tooth indicated by the dotted lines 59f. The type of bit which wears the teeth shown in Figure 5 drags the cones 110 around and is subject to slippage while the bit of this invention drives the cones around and thereby excludes slippage. 115

The form of the invention shown in Figure 6 illustrates a modification of the drive gear 65a and cutter 58a so that the thrust surfaces 69a between the gear teeth and cutter are substantially in the form of a segment of a sphere, which sphere has its center substantially at the intersection of the cutter 120 125 and the axis of the gear. The use of such a 130

axes. With this form of thrust surface between the drive gear and the cutter, a true substantially rolling motion is attained between the drive gear and cutter and the drive gear holds the cutters pressed downwardly and slightly inwardly, relieving any strain tending to spread the cutters.

While the form of drilling bit herein described is well adapted for carrying out the objects of the present invention, it is understood that various modifications and changes may be made without departing from the principles of the invention, and the invention includes all such modifications and changes as come within the scope of the appended claims.

I claim:

1. A rotary well drilling bit comprising: a driving shank; a head rotatable about said driving shank; a plurality of rolling cutters rotatably mounted on said head, said rolling cutters being provided with gear teeth; gear means provided on said driving shank engaging said rolling cutters, said rolling cutters having axes of rotation substantially converging with the axis of the bit and being provided with crushing surfaces and cutting projections adapted to roll on the formation at the bottom of the well bore, said gear means being operative to transmit the vertical load directly from said driving shank to said cutting rollers; and anti-friction bearing means between said head and said driving shank normally inoperative but adapted upon wear of the gear for receiving the vertical load.

2. A rotary well drilling bit comprising: a driving shank; a head rotatable about said driving shank; rolling cutters rotatably mounted on said head; driving means connecting said driving shank with said rolling cutters, the longitudinal load being transmitted from said driving shank directly upon said cutter, said head being normally supported upon said cutters; and anti-friction bearing means normally in an inoperative position and adapted following predetermined wear to receive the load from said driving shank and transmit the same to said head.

3. A driving gear for a rotary well drilling bit comprising: a disc with a bevelled perimeter and a bevelled rectangular boss on one side of said disc; gear teeth on the opposite face of said disc; and walls forming an axial orifice through said disc.

4. A driving gear for a well drilling bit comprising: a disc having faces for locking the disc against torque while permitting axial motion of the driving gear; gear teeth on the lower surface of the disc; and walls forming projections from the disc, and an axial water course through the drive gear.

5. A driving gear for a well drilling bit comprising: a disc having a rectangular boss

at one side and gear teeth on the opposite side, the gear teeth being bevelled back towards the center; and walls forming an axial orifice through the disc and gear teeth, said axial orifice having an expanding throat.

70

6. A rotary well drilling bit comprising: a driving shank; a head rotatable about said driving shank; cutters rotatably mounted on said head and adapted to roll on the formation being drilled, said cutters having frusto-conical cutting surfaces on one end and approximately frusto-conical driving surfaces on the opposite end; a disc arranged between said driving shank and said cutters; and gear teeth on the lower face of said disc engaging said driving surfaces for driving said cutters.

75

7. A rotary well drilling bit comprising: a driving shank; a head rotatable about said driving shank; cutters rotatably mounted on said head and having oppositely disposed cutting and driving surfaces; a disc arranged between said driving shank and said cutters; means for locking said disc against torque while permitting rotation with said drive shank; and gear teeth on the lower surface of said disc engageable with said driving surfaces for driving said cutters.

80

8. A rotary well drilling bit comprising: a driving shank providing a socket; a head rotatable about said driving shank; cutters rotatably mounted on said head and adapted to roll on the formation to be drilled; and a power transmitting member removably positioned in said socket operative to turn said cutters about their axes directly with the rotation of said driving shank when said cutters are engaged with the formation being drilled, said power transmitting member operating to impose vertical load directly from said driving shank to each of said cutters at a point vertically aligned with the approximate center of the position of the cutting faces of the cutters occupying the lower position.

90

9. A rotary well drilling bit comprising: a driving shank providing a socket; a head rotatable about said driving shank; cutters rotatably mounted on said head and adapted to roll on the formation to be drilled; and gear means removably positioned in said socket connecting said cutters with said driving shank, and operating as load transmitting means, said cutters having frusto-conical crushing surfaces and frusto-conical thrust surfaces on opposite ends thereof, the generating line of the conical crushing surface being parallel to the generating line of the conical thrust surface on the other side of the cutter axes.

100

10. A rotary well drilling bit comprising: a driving shank providing a socket; a head rotatable about said driving shank; cutting rollers rotatably mounted on said head; a gear member removably positioned in said socket for driving said cutting rollers with

110

the rotation of said driving shank; and means for imposing vertical load from said driving shank directly upon said cutting rollers at a point vertically aligned with approximately 5 the center of the crushing surfaces of said cutting rollers at the bottom of said drilling bit.

11. A rotary well drilling bit comprising: a driving shank providing a socket; a head 10 rotatable about said driving shank; rolling cutters rotatably mounted on said head; and gear means removably positioned in said socket, said gear means connecting said driving shank and said rolling cutters and being 15 arranged to transmit vertical load to said cutters at points vertically aligned with approximately the center of the crushing surfaces of said cutters which occupy the cutting position.

20 12. A rotary well drilling bit comprising: a driving shank providing a socket; a head rotatable about said driving shank; rolling cutters rotatably mounted on said head, said cutters having conical crushing surfaces and 25 axes of rotation substantially converging at the axis of the bit and rear conical thrust receiving surfaces; and driving means removably positioned in said socket for connecting said driving shank with said rear thrust 30 receiving surfaces of said cutters and directly transmitting vertical load and drilling torque to said rolling cutters.

13. A rotary well drilling bit comprising: a driving shank; walls forming a socket in the 35 lower end of said driving shank; a head rotatable about said driving shank; rolling cutters rotatably mounted on said head, said cutters having conical crushing surfaces and axes of rotation substantially converging at 40 the axis of the bit, said cutters having rear conical thrust receiving surfaces; and driving means removably positioned in said socket, said driving means connecting said driving shank with said rear thrust receiving 45 surfaces of said cutters for directly transmitting vertical load and drilling torque to said rolling cutters.

14. A rotary well drilling bit comprising: a driving shank; a head rotatable about said 50 driving shank; an insert member in said driving shank having a substantially flat lower surface; teeth formed in said lower surface; and a pair of conical cutting members rotatably mounted on said head entirely below said 55 insert member and providing teeth engaging said teeth in said lower surface whereby said insert member takes the vertical thrust imposed upon said conical cutting members.

15. A rotary well drilling bit comprising: 60 a driving shank; a head rotatable about said driving shank; a pair of conical cutting members rotatably mounted on said head; walls forming a socket in said driving shank; an insert member removably positioned in said 65 socket; and interengaging means acting be-

tween said insert member and the walls of said socket whereby said insert member takes the vertical thrust imposed upon said conical cutting members.
